UNITED STATES PATENT OFFICE.

CHARLES A. FOWLER, OF SALT LAKE CITY, UTAH.

AUXILIARY LOCKING BOLT FOR VAULT AND SAFE DOORS.

Application filed April 18, 1924. Serial No. 707,474.

This invention relates to an improvement in auxiliary locking bolts designed especially for use and to be operated in combination with the locking mechanism of vaults and 5 safes.

One of the objects of this invention is to provide an auxiliary locking bolt, which by reason of the adjustability and various lengths of the connecting bars the auxiliary 10 locking bolts can be placed, so they will operate vertically or horizontally as may be desired and most convenient regardless of the location of the permutation lock and cross bolts commonly used on the vaults and 15 safe doors.

Another object of the invention is to provide an auxiliary locking bolt operated from a bell crank lever adapted to cause directly the operation of the auxiliary locking bolt in 20 combination with the movement of the tumblers and bolt of the permutation lock in the movement of locking and unlocking the vault door.

Another object of this invention is to provide 25 an auxiliary locking bolt to work in combination with spaced bolts of the vault door and to lock said bolts with the locking of the vault door.

Another object of this invention is to provide 30 an auxiliary locking bolt that will be automatically thrown in the emergency locking position when the main locking mechanism is tampered with for unauthorized entrance thereto.

Another object of this invention is to provide 35 an auxiliary locking bolt, whereby, the moment the handle of the door is moved downward to move the cross bolts to the locked position the tumblers of the combination lock will be automatically thrown back 40 and set the lock.

With these and other objects in view my invention consists of the following arrangement of parts to be hereinafter described 45 and claimed.

Reference being had to the drawings forming part of this specification and to the figures of reference marked thereon.

Figure 1 is a view showing the inside of 50 the vault door and frame, with my invention applied thereto.

Fig. 1^A is a fragmentary section of the door on line A Fig. 1, showing the drill 55 proof washer placed between the door wall and the casing of the locking mechanism.

Fig. 2 is a fragmentary section of the door

on line 2—2 Fig. 1, showing the means of connecting the first and second auxiliary bolts together.

Fig. 3 is a fragmentary view of the door 60 showing the dial of the spindle, and the handle of the door for throwing the bolts of the door in and out of the locking position.

Fig. 4 is a view showing the inside of the ordinary permutation lock used on many 65 vault doors in an unlocked position.

Fig. 5 is a view of Fig. 4, with the cover thereon, and showing my bell crank lever attached thereto.

Fig. 6 is a fragmentary section view on line 70 6—6 Fig. 5, showing the bell crank lever attached to the cover and to the locking bolt of the permutation lock.

Fig. 7 is an enlarged fragmentary sectional view of the auxiliary bolt within one 75 of the cross bolts shown in the emergency locked position.

Fig. 8 is a section on line 8—8 Fig. 7, showing the means therein for locking the trigger or catch 17.

Fig. 9 is an inside view of a vault door 80 showing the locking mechanism on the door in a locked position and my invention applied thereon and showing it in a locked position.

Fig. 10 is a fragmentary section on line 10—10 Fig. 9 showing the means of connecting the handle L to a bar 70 for moving the cross bolts C, C' and C'' to a locked or unlocked position.

Similar letters and numerals refer to like parts throughout the several views of the drawings.

A indicates the ordinary vault door frame. B the vault door, C, C' and C'' are the cross 95 bolts, D the flange of the door through which the cross bolts project and operate, E represents the casing containing the permutation lock mechanism, F the locking bolt, G the dog, J the tumblers, K the lug within 100 the casing on which rests and slides the locking bolt F and to which the cover H is secured.

1 indicates the bell crank lever, 2' the link, 3 the lifting lever, 4 the upper auxiliary bolt, 4' the lower auxiliary bolt, 5 the sleeve in which the upper auxiliary bolt is placed, 5' the sleeve for the lower auxiliary bolt and 29 the connecting rod between the upper and lower auxiliary bolts.

Having thus described the parts of my invention I will now explain the construc-

tion and applying same to the vault door.

The upper auxiliary locking bolt is a straight bar with a hole in the upper end thereof and the trigger in the lower end thereof. The sleeve 5 in which it rests is secured to the flange D by bolts 60. The lower end of the sleeve being concaved to fit the periphery of the cross bolt C'.

The lower auxiliary locking bolt 4' has a stem 61 projecting upward therefrom with a hole in the upper end thereof. A spring 8' is placed over the stem 61 and then the stem is placed through the hole in the upper end of the sleeve 5' in which the auxiliary locking bolt 4' operates. The sleeve 5' is secured to the flange D by bolts 63. The lower end of the sleeve 5' is concaved to fit the periphery of the cross bolt C'.

A catch can be placed in the end of each of the auxiliary locking bolts if so desired. In describing the construction of the auxiliary locking bolt with the emergency trigger therein I will refer to the bolt 4.

In the lower end of the auxiliary bolt I drill two holes partly through the bolt. One hole 12 runs parallel with the length of the bolt and the other hole 18 drilled horizontal thereof. Through the wall of the bolt and in the end of the hole 18 I cut the slot 19. I now place in the hole 12 the spring 12' and the locking pin 13 and push them in past the hole 18. Now take the trigger 17 placing the tongue 20 through the slot 19. Now take the spring 21 and place it at one side of the trigger 17 so it will not interfere with the operation of the pin 13 in dropping back of the trigger when the trigger is thrown outward or in the emergency locked position. Now I take the screw plug 14 and place it in the hole 12 and the other plug 22 and place it in the hole 18 thus holding the movable parts within the bolt. The trigger is held within the bolt by the wall of the sleeve and the hole in the cross bolt in which the auxiliary bolt rests and operates.

The main operating lever which is a bell crank lever 1 has a slot 23 in the end of the short arm and a hole 24 in the long arm thereof and a hole 25 located at the fulcrum bend thereof, for pivotally connecting the bell crank to the cover H of the casing E.

The connecting rods 3 and 29 and the link 2' are made in many shapes and lengths so as to fit the required placing of the auxiliary locking bolt on the vault door.

In applying the bell crank lever 1 to the permutation lock, I remove the cover H and cut a rectangle hole 26 therein. Now I remove the lock bolt F and drill and thread a hole 27 therein in which I place the pin 28. Now replace the bolt F in the casing and then place on the cover H. Now I take my bell crank lever 1 and place the slot 23 therein over the pin 28 and then take the

set screw 30 place it through the hole 25 and through the hole in the cover H and then into the hole in the lug K in the casing E. The set screw 30 has a shoulder thereon which prevents the screw being turned too far into the hole in the lug K and also prevents the bell crank lever from being too tightly drawn to the cover H to prevent the free movement thereof.

On the top of the casing E I place a staff 75 31 to which I attach one end of the spring 32 to the upper end thereof and the other end I attach to the bell crank lever 1 in the hole 33. This spring draws the bell crank upward upon the turning of the handle L to 80 the downward position as shown in the drawings.

After the location on the door where the auxiliary bolts are to be placed has been decided, I drill a hole 7 through as many of 85 the cross bolts C as there are auxiliary bolts to be placed on the door. As shown on the drawings I have placed two on the door for illustration, but as many may be used as desired.

After the holes 7 and 7' have been drilled in the cross bolts C' and C'', I drill other holes in the flange D of the door and secure the casing of the auxiliary bolts thereto by screws 60 and 63. After the auxiliary bolts 95 have been so placed, I take the link 2' and pivotally attach one end thereof to the hole 24 in the bell crank lever 1 and the other end thereof I attach to one end of the lever 3. Now I drill a hole at any desired place 100 on the door wall and tap same to receive a screw 34. Now I take the screw 34 and place it through the center hole in the lifting lever 3 and then secure the screw within the hole, thus pivotally connecting the lifting 105 lever 3 to the wall of the vault door. I now take the other end of the lifting lever 3 and place it over the end of the pivot pin 37 on the auxiliary locking bolt 4 thus allowing the slot 58' in the end of the lever 110 3 to move over said pivot pin, said pivot pin being soldered to the auxiliary locking bolt 4. Now I take the spring 35 and secure one end thereof to the lifting lever 3 and the other end to a screw in said vault 115 door.

Where there is more than one auxiliary bolt used on the vault door, I use a connecting rod 29 and pivotally connect the upper end thereof to the arm 37 of the auxiliary 120 locking bolt 4 and the lower end thereof I pivotally connect to the eye in the end of the lower auxiliary bolt.

With my invention so applied to the vault door the operation will be as follows.

The movement of the bolt F and the auxiliary bolts 4 and 4' is effected by the direct action of a series of rotating tumblers of the permutation lock. The dog G pivoted at one end to the bolt F carries at the 130

other end a projecting arm 37', which, when the tumblers are arranged in a certain position falls into the notches or gates 38, thus allowing bolt F to be pulled into the casing E by the turning of the tumblers in the unlocking of the door which lowers the bell crank 1, lowering the end 44 of the rod 3 raising the opposite end which in turn lifts the bolts 4 and 8' out of their holes in the cross bolts C' and C'' which will allow the handle L to be turned to move the cross bolts into an unlocked position.

The handle L has a bolt 72 projecting therefrom which passes through a hole in the face of the vault door and entering a hole in the lower end of the link 73 and is secured therein in such a manner that when the handle L is moved it will move the link 73. The upper end of the link 73 has a slot 74 therein through which passes a bolt 75 in such a manner that it will allow the slot to move freely thereon when the handle L is moved to operate the cross bolts, the bolt 75 being secured to the bar 70. The bar 70 connects the cross bolts C, C' and C'' together and is secured to each of the cross bolts by screws 71.

Projecting from the link 73 is an arm P that rests upon the bolt F when it is in a locked position to prevent the movement of the handle L. When the bolt F is in an unlocked position the arm P will be moved downward to the dotted line (a) and the bar 70 will be moved to the dotted lines 90 and the handle will be moved to the dotted line L'. Or in other words the turning of the handle L swings the link 73 which in turn moves the bar 70 which in turn operates the cross bolts. In the locking of the vault door by turning the dial or spindle 39 the arm 37' is drawn up by the tumblers and the bolt F will be moved outward as shown by dotted lines F' and by turning the tumblers the arm will ride upon the periphery of the tumblers. And in this movement the pin 28 in the bolt F projecting through the slot 26 in the cover H and into the slot 23 in the bell crank lever 1 moves this end backward and the other end upward as shown by dotted lines 40. This movement through the link 2' raises the end 44 of the lifting lever 3 and lowers the other end, which is also operated by the springs, thus allowing the auxiliary bolts to enter the holes 7 and 7' in the cross bolts C' and C'' at the same time that the vault door is locked by the turning of the tumblers.

After the vault door has been unlocked and opened and the handle L is moved back or downward as shown in the drawings the spring 32 in combination with the other springs 8' and 35 moves the bell crank lever 1 to the position shown by dotted lines 40

which moves the tumblers and the vault bolts become locked. And by so doing it makes a day lock. To keep the bolts in an unlocked position the handle L must be kept in the position shown by dotted lines L'.

When the cross bolts are locked the movement of the tumblers to unlock them at the same time removes the auxiliary locking bolts from the holes in the cross bolts C' and C'' thus all the locks on the door work in action together.

In the above operation the safe can be kept locked during the day, as the movement of the tumblers by the bell crank lever 1 does not throw them far enough out of line to make a working set of them. Or in other words the combination will not have to be worked as in opening the door, all that is to be done is to turn the spindle 39 back to the stopping number on the dial and then the handle L can be raised as shown by dotted lines L'.

With this locking means on the vault door, it is almost impossible for the door to be closed and locked while any one is within the vault. Or to be closed by robbers in case of robbery. If the robber should force the parties into the vault he would find the handle locked and could not operate it.

While my invention makes the lock of such quick action, in the event that a robbery was being committed any one that was able to reach the door could close it and push the handle downward and the safe would become locked.

In the event that the vault door was tampered with to secure entrance thereto by some other means than by working the combination, such as burning or driving in the spindle, the action of the auxiliary bolts will be as follows.

In burning, the heat would soon melt the soft metal of which the auxiliary bolt is attached to the lever 3 this allowing the auxiliary bolts to drop through the holes in the cross bolts. As they are already part way through the cross bolts there is no chance for a failure of them not working and dropping through the holes in the cross bolts. In the event that the heat did not melt the soft metal, the heat would melt the lifting lever 3 as soon as it came in contact therewith.

If the spindle should be driven in, the result would be that the cover H would be knocked off the casing E, the connection between the bell crank lever 1 and the lever 3 would be broken or the lever 3 would be broken. These connections are of very weak metal and will be broken with very little pressure, after this has happened the auxiliary bolts will drop into the holes in the cross bolts.

When the auxiliary bolts have passed through the cross bolts as shown in Fig. 7, the tongue 20 of the trigger 17 is forced out of the slot 19 by the spring 21 thus allowing the locking pin 13 to drop down behind the trigger into the lower end of the hole 12, thus locking the trigger so it is impossible to push it back into the hole 18 until the pin 13 has been replaced.

10 To open the door after the auxiliary locking bolts have been thrown into the emergency position, the following steps are taken:

15 When the auxiliary bolts are placed on the door a measurement of their location is taken and placed away for record. In opening the door this record must be used to get the exact location of the auxiliary bolts. At this location a hole is made into the door to allow the necessary tools to be placed therein 20 to remove the screw 14 in the bottom of the auxiliary locking bolt. After the screw 14 has been removed the pin 13 will drop out to the floor of the vault. After the pin 13 is out of the way the tongue 20 can be put back into the slot 19 by the use of a rod or screw driver being placed through the hole in the vault door, then the auxiliary locking bolt can be moved up through the hole in the cross bolt thus allowing the cross bolts to 25 be moved back to unlock the vault door.

30 After the door has been opened the broken parts are all removed and new parts placed therein. The auxiliary bolts are left in the same position or changed to some other location on the door.

35 Having thus described my invention what I claim as new and desire to secure by Letters Patent, is:—

1. An auxiliary locking bolt in combination 40 with a vault door, a locking device on the door including a bolt mechanism and a combination mechanism, a bell crank lever operated by said combination mechanism, said auxiliary locking bolt secured to said vault door, adapted to engage a hole in one 45 of the cross bolts of said door and lever means for connecting said bell crank lever with said auxiliary locking bolt.

50 2. An auxiliary locking device in combination with a vault door, a locking device on the door including a cross bolt mechanism and a combination mechanism, a bell crank lever pivotally mounted on the casing of said combination mechanism, the auxiliary locking device operated by the bell crank lever, and a pin secured to the bolt of said combination mechanism for operating said bell crank lever with the movement of the bolt by said combination mechanism.

55 3. An auxiliary locking bolt in combination with a vault door, a locking device on the door including a bolt mechanism and a combination mechanism, a lever pivotally mounted on the cover of the casing of said combination mechanism and arranged in

parallel relation to said cover, the auxiliary locking bolt operated by the bell crank lever, and a pin attached to the locking bolt of said combination mechanism, said pin passing through a slot in said cover and engaging with a slot in said bell crank lever for the operation of said lever in the movement of said bolt by the combination mechanism.

4. An auxiliary locking bolt in combination 75 with a vault door, a locking device on the door including the bolt mechanism, and the permutation lock mechanism with a bolt and tumblers therefor, a bell crank lever pivotally mounted on the cover of said permutation lock, the auxiliary locking bolt operated by the bell crank lever, said bolt having a pin projecting therefrom, said pin passing through a slot in said cover and engaging a slot in said bell crank lever for the operation 80 of said bell crank lever in the movement of said bolt by said tumblers.

5. An auxiliary locking device in combination 85 with a vault door, a locking device on the door including a bolt mechanism, and a permutation locking mechanism having a bolt and tumblers therefor, a bell crank lever pivotally mounted on the cover of said permutation lock, the auxiliary locking bolt operated by said bell crank lever, said bolt having a pin projecting therefrom, said pin passing through a slot in said cover and engaging a slot in said bell crank lever, a spring one end thereof supported by a staff secured to the casing of said permutation 90 locking mechanism and the other end thereof secured to said bell crank lever said spring for automatically operating said bell crank 95 to throw said bolt and tumblers into their locked position when the handle on the vault door is moved downward.

6. An auxiliary locking bolt in combination 100 with a vault door having a flange adjacent to the edge thereof, a locking device on the door including the combination mechanism, a plurality of spaced bolts arranged to be projected through said flange and a bar connecting said bolts, an auxiliary locking bolt consisting of a supporting member carried on the door flange, a bell crank 105 pivotally mounted on the casing of the combination mechanism, a rod secured to said auxiliary bolt and extending in parallel relation to the door and connecting said auxiliary bolt to said bell crank lever and 110 means for operating said auxiliary bolt.

7. An auxiliary locking bolt in combination 115 with a vault door having a flange adjacent to the edge thereof, a locking device on the door including a combination mechanism, a plurality of cross bolts arranged to be projected through the flange and a bar connecting said bolts, a bell crank lever, said auxiliary locking bolt consisting of a supporting member carried on the flange, a 120

- rod secured to said auxiliary bolt and extending in parallel relation with the door and connecting with said bell crank lever, said bolt being fulcrumed to the door wall
- 5 5 another rod connecting said auxiliary bolt with another auxiliary bolt, said rods and bell crank lever for operating said auxiliary bolts when said combination lock is locked and unlocked.
- 10 8. An auxiliary locking device in combination with a vault door, a locking device on the door including the bolt mechanism and combination mechanism, comprising a bell crank lever pivotally carried by the casing of said combination mechanism, a pin placed in the bolt of said combination mechanism, said pin passing through a slot in said cover and entering a slot in said bell crank lever, means for pivotally connecting said bell crank lever to said casing cover, a sleeve member mounted on said door frame, a bolt operated in said sleeve member, another sleeve member carried by said door, another bolt operating in said other sleeve member, said bolts to engage holes in the cross bolts of said door, means for connecting said bolts to said bell crank, means for connecting said bolts together, means for securing said sleeves to said door and means for operating said bolts.
- 15 9. An auxiliary locking device in combination with a vault door, a locking device on the door including a bolt mechanism and a combination mechanism, comprising a sleeve member mounted on said door, a locking bolt carried and operated in said sleeve member to engage with one of the cross bolts of said door, an operative member to operate the bolt in a coactive movement with the combination mechanism, means for projecting said bolt through said cross bolt when released from the operating member, a bell crank member carried by the casing of said combination mechanism, means for connecting said bolt with said bell crank lever and means for connecting said bell crank lever with said operating member.
- 20 10. An auxiliary locking device in combination with a vault door, a locking device on the door including a combination mechanism and a bolt mechanism, comprising a bell crank lever pivotally carried by the casing of said combination mechanism, the auxiliary locking device operated by the bell crank lever, a pin placed in the bolt of said combination mechanism, said pin passing through a slot in said cover and entering a slot in the arm of said bell crank lever and means for pivotally connecting said bell crank lever to said cover.
- 25 11. In combination with a vault door and a locking device on the door including a bolt mechanism and a combination mechanism, an auxiliary locking device consisting of a supporting member mounted on the door flange, bolts carried by said supporting member, means for projecting said bolts into the locked position by the movement of the combination mechanism, and means for placing said bolts in the emergency locking position upon the breaking of the combination mechanism.
- 30 12. The combination with a vault door having a flange extending adjacent to the edge thereof, a locking device on the door including a plurality of bolts arranged to project through said flange and a bar connecting said bolts, a sleeve secured to said flange a bolt slidably mounted in said sleeve, a trigger catch in the lower end of said bolt operated by a spring within an opening in said bolt, a locking pin for said catch in another opening in said bolt, a spring for operating said pin and means for securing said catch and pin within said bolt.
- 35 13. An auxiliary locking device in combination with a vault door, a flange extending adjacent to the edge thereof, a locking device on the door including a plurality of spaced bolts arranged to project through said flange and a bar connecting said bolts, a sleeve secured to said flange, a bolt slidably mounted in said barrel, said bolt having two holes in the lower end thereof, a catch placed in one of said holes operated by a spring in said hole and secured therein by a screw plug, a locking pin in the other of said holes and operated by a spring placed therein, said pin for locking said catch in the emergency position and means for holding said pin and spring in said other hole.
- 40 14. An auxiliary locking device in combination with a vault door having a flange extending adjacent to the edge thereof, a locking device on the door including a combination mechanism and a bolt mechanism arranged to project through said flange and a bar connecting said bolt mechanism, a bell crank lever rotatably mounted on the cover of said combination mechanism, a pin attached to the locking bolt of said combination mechanism, said pin passing through a slot in said cover and engaging with a slot in said bell crank lever, said pin for the operation of said bell crank lever in the movement of said locking bolt by the combination mechanism, the casing of said combination mechanism having a staff thereon with one end of a spring attached thereto, the other end of said spring being attached to said bell crank lever, said spring to draw said bell crank lever in the locked position, a bolt having a supporting member secured to said flange, a rod pivotally secured to said door and connecting said bolt with said bell crank lever, another rod attached to said bolt and connecting with another bolt within a casing secured to said door flange

and means in said bolt for locking it in the emergency position.

15. An auxiliary locking device in combination with a vault door having a flange adjacent to the edge thereof, a locking device on the door including a combination mechanism a plurality of cross bolts arranged to be projected through said flange and a bar connecting said bolts, said auxiliary locking device consisting of a bell crank member pivotally mounted on the casing of said combination mechanism, an operative member within said casing and projecting through a slot in said casing to engage said bell crank member, a supporting member carried on the flange of said door, a rod connecting a bolt member within said supporting member with said bell crank member, said rod being fulcrumed to the door wall, another rod connecting said

bolt member with another bolt member within another supporting member secured to said flange, said rods and bell crank member for operating said bolts within said supporting members when said combination mechanism is moved in locking and unlocking the locking mechanism of the door. 25

16. In combination with a vault door and a locking device on the door including a bolt mechanism and a combination mechanism, auxiliary locking bolts secured to said vault door, a bell crank lever operated by said combination mechanism, said auxiliary bolts to engage holes in the cross bars in said door and means for connecting said bell crank lever with said auxiliary locking bolts. 30 35

In witness whereof, I affix my signature.
CHARLES A. FOWLER.
